CLAIM

I claim, the ornamental design of a combined triplex receptacle block and junction block, as shown and described.

DESCRIPTION

FIG. 1 is a right side view of my combined triplex receptacle block and junction block in accordance with the present invention, with FIG. 1 illustrating the position of my combined triplex receptacle block and junction block as it may be engaged with a junction block. The side of the invention shown in FIG. 1 is plain and unornamented and forms no part of the claimed design.

FIG. 2 is a front elevational view of the invention of FIG. 1.

FIG. 3 is a left side view of the invention of FIG. 1.

FIG. 4 is a left end view of the invention of FIG. 1.

FIG. 5 is a rear elevation view of the invention of FIG. 1.

FIG. 6 is a right hand end view of the invention of FIG. 1.

FIG. 7 is a perspective and partially exploded view of the combined triplex receptacle block and junction block of the present invention, showing the combined triplex receptacle block and junction block as it may be engaged in a front side of a junction block.

FIG. 8 is a perspective view of my combined triplex receptacle block and junction block in accordance with the present invention, with FIG. 8 illustrating my combined triplex receptacle block and junction block as assembled into the front side of a junction block.

FIG. 9 is a perspective and partially exploded view of the combined triplex receptacle block and junction block of the present invention, with FIG. 9 illustrating the positioning of my combined triplex receptacle block and junction block as it may be engaged with a rear side of a junction block; and,

FIG. 10 is a perspective view of my combined triplex receptacle block and junction block in accordance with the present invention, with FIG. 10 illustrating my combined triplex receptacle block and junction block as assembled into the rear side of a junction block.
